(57) **CLAIM**

The ornamental design for an end cap for a luminaire, as shown and described.

DESCRIPTION

FIG. 1 is a perspective view of a first embodiment of the new design for an end cap for a luminaire as seen from the top, rear, left side;

FIG. 2 is a perspective view thereof, as seen from the top, front, right side;

FIG. 3 is a perspective view thereof, as seen from the front, left side;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof; and

FIG. 9 is a bottom plan view thereof.

FIG. 10 is a perspective view of a second embodiment of the new design for an end cap for a luminaire as seen from the top, rear, left side;

FIG. 11 is a perspective view of the second embodiment, as seen from the top, front, right side;

FIG. 12 is a perspective view of the second embodiment, as seen from the front, left side;

FIG. 13 is a front elevational view of the second embodiment;

FIG. 14 is a rear elevational view of the second embodiment;

FIG. 15 is a right side elevational view of the second embodiment;

FIG. 16 is a left side elevational view of the second embodiment;

FIG. 17 is a top plan view of the second embodiment; and,

FIG. 18 is a bottom plan view of the second embodiment. The broken lines illustrate portions of the end cap for a luminaire and form no part of the claimed design.

1 Claim, 10 Drawing Sheets
